WIRE SPOOL

Jacob J. Mitnick, Highland Park, Ill., assignor to
Magnet Wire, Inc., Chicago, Ill.

Application July 21, 1954, Serial No. 444,756

2 Claims. (Cl. 242—123)

This invention relates generally to spools, and more particularly is concerned with the construction of a spool for carrying fine wire of the type used in making windings and coils for electrical components such as transformers and ballasts.

Spools of the type here described have two principal purposes, the second of which is perhaps the most important of the two. The first purpose is to serve as a carrier or storage receptacle for wire. The wire is manufactured and wound upon spools of this type, and these spools are thereafter stored, and/or transported to the ultimate user. While some users may not require the spool thereafter except as a means for carrying the wire, most users of the fine wire with which this invention is principally concerned will utilize the same spool for the second purpose which will be mentioned. In the cases where the user purchases the wire in large reels or manufactures his own wire, he will rewind the wire upon this type of spool before using the same.

The second purpose for the spool is to hold and permit feeding of the wire to winding machines. In most winding machines there are provided a plurality of spool mounting spindles with braking, tensioning, feeding and other functions so that the wire from the spools is led directly to the winding spindle upon which are formed coils for use in electrical apparatus.

Spools of structure of this invention may be made in large sizes for purposes of carrying heavy cable and rope—they may be several feet in diameter and made out of steel or other tough materials. It is intended primarily, however, that the spools be used for fine wire of the type used in ballasts for fluorescent fixtures, such as for example from 16 to 40 gauge, and hence that such spools be of the order of six inches in diameter and made of aluminum and similar light alloys. It is believed that the maximum of advantages is obtained in this smaller size.

Several objections to prior structures have not been overcome in the prior art, and among these are the lack of combined strength and lightness in weight which it is an important object of the invention to achieve.

Another objection of the prior structures lies in the absence of hub strength which gives rise to likelihood of transverse collapse and denting. The invention contemplates the provision of a novel structure eliminating this in a highly economical and efficient manner.

Prior structures have also been constructed of a great many parts—have been difficult to assemble and expensive to manufacture—have not provided sufficient strength in their end plates—have required added members to prevent crushing or distortion of the end plates—have been so constructed as not to utilize to maximum advantage modern efficient manufacturing processes. All of these disadvantages have been overcome by the invention.

Additional and specific objects of the invention are the provision of a novel spool having its hub formed of two opposed identical parts, the provision of a novel web

2

of simple structure and great strength, the provision of a novel method of fabrication and assembly of the spool.

Other objects will become apparent as the description of the invention proceeds, in connection with which there has been illustrated and described a preferred embodiment showing the practical construction of a wire spool utilizing the invention. Modified forms are also referred to. The description and details of the preferred structure are only by way of example and not limitation.

In the drawings, in which like characters of reference are applied to the same or equivalent parts throughout the several figures of the drawings:

Fig. 1 is a top plan view of the spool embodying the invention.

Fig. 2 is a side elevational view of the spool, which like the other views, do not illustrate the wire or the spool mountings.

Fig. 3 is an enlarged sectional view through the spool taken generally along the line 3—3 of Fig. 1 and in the indicated direction.

Fig. 4 is a fragmentary enlarged sectional view showing a detail of assembly of the end plate of the spool.

Fig. 5 is a sectional view taken through the spool along the line 5—5 of Fig. 3 and looking in the direction indicated, with portions broken away to show certain details.

Figs. 6 and 7 are fragmentary sectional views through modified forms of the invention, and Fig. 8 is a fragmentary sectional view taken through the core of the form of Fig. 6 along the line 8—8 and in the indicated direction.

Generally the spool is formed of a pair of cup-like halves having annular lips, ledges or extensions about their open ends and provided with seating buttons on their bottom walls. A pair of such cups is arranged bottom to bottom, with the buttons aligned so as to mate, such that the combined assemblage of bottoms gives a central, strong double walled web through the interior of the spool. The sides of the cup-like halves form the hub. A central post or core of appropriate configuration is mounted in the center of the cup-like halves, and the open ends capped in a novel manner with plates suitably seated over the annular lips, ledges or extensions and engaging the free ends of the post.

Specifically referring to the drawings, the spool is designated generally by the reference character 10 and same has a smooth surfaced hub 11 of relatively large diameter for mounting the wire, end plates of composite construction to be described, and a central hollow cylindrical core 13 by means of which the spool 10 may be mounted upon a suitable spindle (not shown) for use.

It will be seen that the hub 11 and the interior faces of the end plates 12 are formed of a pair of cup-like members 15 and 16 which are of identical structure except secured one to the other bottom to bottom. The designations 15 and 16 are merely to enable reference to upper and lower cups, as they will be hereinafter termed, for purposes of explanation. Each of the cups 15 and 16 comprises a bottom wall 18, an integrally formed cylindrical side wall 19, and an annular ledge or extension 21 at the open end of the cup. Each of the bottom walls has a pair of upset buttons 23 and a pair of perforations 25 whose diameter and form is such as to matingly engage with similar buttons.

The buttons 23 and perforations 25 are spaced 90° apart about the bottom wall 18 of each cup 15 and 16, and radially equidistant from the axis of the cups and hence the axis of the spool 10, as will be apparent. The buttons protrude outwardly of the respective cups so that they may engage in the perforations 25 of the facing wall

18. Since there are two buttons 23 and two perforations 25 identically placed in each bottom wall, the cups are identical and may be made from the precise same die, by

drawing the same in the conventional punch press. In assembling the cups 15 and 16, they are rotated one relative to the other, either 90° or 180° prior to assembly, depending upon whether the buttons 25 (or perforations 23) are placed 90° or 180° from one another.

As seen in Fig. 5, the bottom view of the wall 18 of the lower cup 16 reveals that there is a button 23 formed on the left and, on the bottom (as viewed in Fig. 5) of the wall 18, while a perforation 25 on the right and another on the top receive the buttons 23 of the wall 18 of the cup 15. Actually in this view one cannot see the buttons of the wall 18 of the lower cup 16 because they are formed through the upsetting of metal from the wall. All that is visible at the location of each button is a cylindrical depression, which is designated 23'.

This type of construction requires that the cups 15 and 16 be rotated 180° relative one another before assembly.

With the cups arranged as shown in the drawings, and before any other step is taken in the assembly of the spool 10, the bottom walls 18—18 are spot-welded together at circumferentially spaced points indicated at 27. This joins the two walls into a double web or partition which for reference can be collectively designated 31. This is the principal constructional feature of the spool since it provides great strength and resistance to crushing in the center of the hub 11 without weight of consequence, and without any complex structures. Where the cups 15 and 16 meet there may be a slight seam 32, the size of which depends upon the radius of the corner of the cups. Depending on the size of wire to be wound upon the spool 10, this seam may or may not be ground smooth, or filled with any suitable filler such as plastic, solder or the like.

At the center of each of the walls 18 there is a circular opening, the two openings combining to form a passageway 33 the diameter of which is such as to fit the central post or core closely, but slidingly. Three different types of cores designated generally 13, 36 and 37 are illustrated respectively in Figs. 3, 6 and 7, but that of Fig. 3 is preferred.

After the assembly of the cups 15 and 16, the core is inserted into the passageway 33. This core consists of an elongate hollow member 40 of generally cylindrical formation, but having a centrally located annular bulge 41 formed therein, and end bulges 42 and 43. The end bulges form shoulders such as shown at 45, for example and prior to assembly of the end plate the free ends 47 of the core 13 extend axially from the shoulders 45 as indicated at 47' by broken lines in Fig. 3. The formation described provides a considerable bearing space along the length of the core, defined by two cylindrical elongate sections 48 and two short sections 49 at the ends. Thus a spindle or shaft (not shown) has plenty of surface either for bearing purposes or for frictional engagement purposes. Likewise, the end sections 49 provide good support for some types of conical clamping spindles that are used on winding machines.

As will be seen from the drawings, the cores 13, 36 and 37 in each case are formed of identical halves, providing an abutting seam 51. This makes for ease in fabrication, for economy in production, and provides no difficulties in assembly. Since the structure of the spool is such that all parts are securely held in assembled relationship, there is no need for welding the two halves of each core together although if desired this may be done. The notches 52 are typical of the ends of cylindrical members which are peened over as ends 47 are during assembly.

Presuming for the moment that the core 13 is now in the passageway 33, but that the cup ends are open, it will be obvious that the extensions or ledges 21 are not bent over as shown at 54 to form the rim, but are co-planar with the ledges 21 as indicated by the broken lines 54'. The extensions or ledges 21 are also co-planar with

the shoulders 45, so that they may together support the capping plate 56. The extensions 21 are each provided with a pair of upset protuberances or buttons 57 diametrically arranged. The capping plate is a disc of dimension 5 to fit inside the diameter of the extensions or ledges 21 leaving a considerable overlap. The edge of the capping plate 56 is provided with a downwardly offset, continuous flange 59 whereby the resulting formation provides a strengthening annular bend 60 resisting distortion of the 10 end plate 12. Radially inward of the bend 60 there is provided an inwardly directed circumferential crimp 62 which forms another strengthening formation.

Each of the formations are pressed inwardly an amount equal approximately to the thickness of the capping plate 15 56 so that when placed upon the extensions 21, the flanges 59 and the inner bulges of the crimps 60 rest upon the face of the extension 21 with which the respective capping plate is associated. On opposite sides of the center, in the crimps 62 there are provided perforations 64 which 20 are radially and circumferentially aligned with the buttons 57 so that when assembled upon the extensions 21, the capping plates 56 will seat perfectly coaxially with the remainder of the assembled parts.

At its center, each of the capping plates 56 has a large 25 opening 66 which is surrounded by an inwardly offset annular flange 67 of the same formation as the flange 59. The opening snugly fits the core 13 at the sections 49 and hence the flanges rest upon the shoulders 45. When the assembly step which consists of placing the plates 56 30 upon the extensions 21 is carried out, all of the edges 54 are extended, and the core ends 47 are not crimped. After assembly, the rims 54 are formed by crimping the portions 54' over and upon the flanges 59, and the rounded core ends 47 are formed by crimping the portions 47' over and upon the flanges 67. Obviously, through the use of suitable dies and fixtures, this operation can be a simple and speedy one. The end plates 35 may have openings 69 to cooperate with the usual offset spindle pin (not shown).

40 It will be seen from the description that there is no need to provide castings of any kind; that there are only six parts which includes the two halves of the core 35; that all of the parts are simple stampings or drawings; that they are assembled through the use of seating means 45 which prevents any error or misalignment of the parts; that the only fastening means consists of a few welds about the web 31, and these welds are in the interior of the spool; that the remainder of the spool is assembled in a simple and efficient manner; and that a great deal 50 of strength through the use of ingenious arrangement of the parts has been built into the spool without using excessive material.

In addition, the resulting article is capable of withstanding excessive abuse without being the worse for the 55 wear because of the novel structure.

With respect to the core structures illustrated in Figs. 6, 7 and 8, Figs. 6 and 8 represent a structure in which, instead of a formed core 13, the core 36 is made up of a center uniformly cylindrical member 70 which may be 60 formed of a pair of identical halves abutted at 71. The surface on the interior is thus continuous. The free ends 72 are crimped over as are the ends 47 in the core 35. In order to provide a shoulder for the support of the flanges 67, an inner telescoping sleeve 74 is disposed about the member 70, the length thereof being the distance 65 between opposing flanges 67.

Fig. 7 eliminates the sleeve 74 by providing the member 78 (which may be split) with end formations similar to the end formations of the core 35. An inward annular crimp provides a shoulder 79 for seating the flanges 67 and the peening over of the free ends 80 upon the flanges 67 secures the capping plates 56. The resulting core 37 has two narrowed bearing portions 81 top and bottom, the diameter of the remainder of the member 78 being 75 greater.

It is believed that the invention has been fully explained so as to be perfectly clear to those skilled in the art, such that further explanation may be dispensed with, but it is desired to point out that variations in the details such as formation of the parts, size, dimensions and proportions are capable of being made without departing from the spirit or scope of the invention as defined in the appended claims.

What it is desired to secure by Letters Patent of the United States is:

1. A spool for wire comprising, a pair of cups each having cylindrical side walls, a bottom wall with a central opening, and an annular extension on the open ends of the side walls, the bottoms having cooperating seating means for positioning same in juxtaposition with the annular extensions on the opposite ends of the resulting formation, said means comprising a plurality of outwardly protruding button and socket formations and spaced one from the other so as to obtain registry of each button with a socket, means spaced radially inward of the edges of the bottoms rigidly joining said bottoms face to face, an annular capping member having an open center secured to each annular extension, and a hollow core member secured between the open centers and through said central opening, assembled to the spool after joining the cups, but before assembling the capping members, said core having a centrally located annular upstanding bulge and the bottoms are seated on said bulge in the central opening.

2. A spool for wire comprising, a pair of cups each 30

having cylindrical side walls, a bottom wall with a central opening, and an annular extension on the open ends of the side walls, the bottoms having cooperating seating means for positioning same in juxtaposition with the annular extensions on the opposite ends of the resulting formation, said means comprising a plurality of outwardly protruding button and socket formations and spaced one from the other so as to obtain registry of each button with a socket, means spaced radially inward of the edges of the bottoms rigidly joining said bottom face to face, an annular capping member having an open center secured to each annular extension, and a hollow core member secured between the open centers and through said central opening, assembled to the spool after joining the cups, but before assembling the capping members, said core having a centrally located annular upstanding bulge and the bottoms are seated on said bulge in the central opening, said core having an upstanding shoulder formation on each free end thereof and the valley portions between said shoulders and bulge provide bearing spaces along the length of the core for engagement with a spindle or shaft inserted in the core.
